UNITED STATES PATENT OFFICE.

JOHN BRANDWOOD, THOMAS BRANDWOOD, AND JOSEPH BRANDWOOD, OF ELTON,
BURY, ENGLAND.

APPARATUS FOR DYEING WOUND YARNS ON SPINDLES.

Application filed December 22, 1923. Serial No. 682,301.

To all whom it may concern:

Be it known that we, JOHN BRANDWOOD, THOMAS BRANDWOOD, and JOSEPH BRANDWOOD, subjects of the King of Great Britain and Ireland, and residents of Elton, Bury, in the county of Lancaster, England, have invented certain new and useful Improvements in Apparatus for Dyeing Wound Yarns on Spindles, of which the following is a specification.

This invention relates to apparatus for the treatment with liquids of yarn packages, e. g. cheeses, and the subsequent handling of such yarn packages for the drying and other treatment of same, the treatment of liquids being effected by placing the cheeses on spindles, compressing same if desired, and passing fluid through them by means of a pump in the manner described for instance in our pending application No. 640539 of the 21st May, 1923, wherein the spindles employed are fluted. In such treatment the fluid for instance dye fluid, passes from a pump to a lower chamber, thence to the flutes of the various spindles of the apparatus, and thence through the yarns mounted on the spindles and into the dye bath in which the apparatus is fitted, the flow of liquor being reversible. In some cases it is found that there is difficulty in removing all the cheeses after liquor treatment, as the yarns contract owing to such treatment and compress the cheeses upon their dyeing spindle, and further it is not in all cases expedient to employ the process described in our said pending application viz: to slip the cheeses off their spindles and pass each directly on to a central holder of the same cross section as the dyeing spindle.

The present invention has for an object an apparatus for dyeing yarn packages on spindles in such a manner that they may be easily removed therefrom, thus saving possible waste of yarn and also saving time in the operation, with subsequent mounting of the cheeses on central holders in a rapid and extremely simple and inexpensive manner. In carrying it into effect in the treatment of yarns wound in the form of cheeses, we take the cheeses to be treated, and remove the central paper or like tube on which they have been wound, this operation being easily effected by pressing the tube out. The cheeses are then placed on dyeing

spindles, one above another until each spindle is filled, and compressed if desired upon the spindles. These spindles are not of equal diameter throughout; they taper upwardly to any desired or convenient degree, and are held in position in the apparatus in such a manner that they may when desired be displaced downwardly in relation to the cheeses held thereon. After the treatment on the spindles is completed the spindles are loosened and pressed downwardly, thus breaking contact of the inner windings of the yarn cheeses with the spindle itself. The cheeses may then be rapidly removed, as they are all now loose on their spindles, and dried in any convenient manner.

The invention will now be fully described with reference to the accompanying drawings, wherein:—

Figure 1 is an elevation partly in section of an apparatus comprising a plurality of dyeing spindles, only some of which are shown for clearness of description;

Figure 2 is a plan view showing the arrangement of the spindles and of a liquor chamber at the lower end of the apparatus.

Figure 3 is a detail view of a fastening device for securing the spindles. Figure 4 is a detail view of a device for pressing the dyeing spindles downwardly in the apparatus.

Referring to the drawings, Figure 1, 5 is a chamber having an upper plate 6 and a lower opening 7 with a circular flange member 8. The flange member allows of the placing of the whole apparatus in a dyeing kier as described in the specification to United States Letters Patent No. 1174662. Preferably the chamber is arranged with a circular internal wall 9 having openings 10 for a purpose to be hereinafter explained. 11 indicates dyeing spindles which are fluted as described in our pending application for United States Letters Patent Serial No. 640539 but according to our present invention the spindles 11 taper upwardly, to any desired degree. This taper is shown exaggerated at the right hand in Figure 1. For the purpose of the invention this taper may be very little. 12 is a central rod which as shown is screwed into the plate 6 which is tapped for the purpose. This central rod 12 may be a plain rod having a hook or ring at the

upper end thereof, or it may be arranged to receive a special pressing apparatus to be hereinafter referred to. 13 indicates cheeses placed upon the spindle 11.

- 5 Screwed into the plate 6 are a number of annular plates 14 having extensions 15 the lower ends of which are threaded for the purpose. The internal diameter of these plates and the extensions 15 is such that a 10 spindle 11 will fit therein with a fairly tight sliding fit. One of these plates—hereinafter referred to as spindle holders—is provided as the holder for each dyeing spindle in the apparatus. At one side of 15 each spindle holder is fitted the stop or slide member 16 the inner end of which projects through the wall of the tubular extension 15 of the holder to engage between two flutes of the dyeing spindle. The slide member 20 is threaded to receive a nut 17 to hold it in position. At a point diametrically opposite to the orifices formed for the insertion of the slide member end the tubular extension 15 is tapped to receive the threaded end 18 of a thumbscrew 19—see Figure 25 3—which when screwed in position serves to keep its spindle 11 in position within the plate 6. Upon the lower end of each spindle 11 is fitted a plate 20, secured to 30 the spindle in any convenient manner, which serves to limit the upward movement of the spindle within its holder 14.

In carrying out the operation of dyeing of the cheeses we proceed as follows:—The 35 spindle 11 being in position as shown in Figure 1 and held therein by the thumbscrews 19, a washer 21 is placed upon each spindle holder 14. Cheeses 13 from which the central paper or like tubes have been 40 removed are then placed upon each spindle until the latter is full. After the apparatus has been thus charged the cheeses may be compressed upon each spindle by any approved means. When the cheeses are thus 45 prepared, the dyeing proceeds by the forcing of the dye liquor into the chamber 5 through openings 7 from a pump (not shown), the liquor proceeding up the flutes of the spindle 11, which are open to the 50 chamber as will be evident from the drawing Figure 1, and thence through the yarns of the cheeses 13 into the dye bath or receptacle in which the whole apparatus is placed. The flow of liquor may then be 55 reversed and this continued as long as necessary. When the liquor treatment is completed, the thumbscrew 19 is then removed from a spindle 11, thus leaving the latter free and pressure is applied to the 60 top of the spindle to force it downwardly, the depth of the liquor chamber 5 allowing for this. As the spindle moves downwardly whilst the holder 14 and the cheeses remain stationary, it will be evident that when the 65 downward displacement is complete, any

cheese 13 will be on a diameter of its spindle 11 which is less than the diameter on which it was originally placed, the cheeses 13 being thus loose on their spindle. They may then be removed easily, and dried in any suitable 70 manner, as for instance in a drying machine of known construction.

Although we do not confine ourselves to any particular method of pressing the spindles 11 downwardly we may usefully employ the apparatus described in our co-pending application No. 682,303 for this purpose. In that specification there is described a lever which is fulcrumed on a central rod—12 in the present description 80 and drawings—and bearing a pressure member which presses downwardly upon a top plate placed on each dyeing spindle. In order to utilize this for the pressing downwardly of each spindle 11, we may employ the pressure member 22 shown in Figure 4 of the drawings hereto annexed. The pressure member may be of the configuration shown, and have a recess 23 formed in the upper face thereof. A pin placed in 90 a hole in the lever before mentioned may fit into this slot, and downward pressure of the said lever will through the pressure member, force the spindle 11, upon which the pressure member has been placed, downwards. If desired the upper end of each spindle may be slotted as shown at 23 Figure 4, and lugs 24 be formed upon the pressure member to fit in the said slots.

When the cheeses have all been removed 100 the spindles 11 are drawn up to the position shown in Figure 1 and the screws 19 replaced to hold the said spindles in position for a further dyeing operation.

We have described the invention as being 105 applied to yarn packages a plurality of which are placed on a single dyeing spindle, the latter being of a length sufficient to take such plurality of packages. It will be obvious however that if found convenient the 110 invention may be applied to yarn packages which are mounted single upon dyeing spindles, the spindles of course being tapered. Also, although we have referred to fluted 115 spindles, the invention may be equally applied to tubular perforated spindles, as, by tapering the latter, the dyeing and subsequent handling of the yarn packages can be carried out in exactly the same manner as hereinbefore described.

It will be understood that we do not claim in this application the method per se of dyeing cheeses in the compressed state or otherwise by means of mounting them on fluted dyeing spindles which are in communication with the liquor chamber.

We claim:—

1. A support for cheeses of yarn, comprising a hollow chamber for dye provided with a spindle holder at its top having a plate 130

for supporting the cheeses, an upwardly tapering spindle for positioning the cheeses having its lower end portion slidable downwardly in the spindle holder and provided 5 with passages for dye which communicate with the said chamber, and a fastening device for locking the spindle in the spindle holder at will.

2. A support for cheeses of yarn, comprising 10 a hollow chamber for dye having a hole in its top, a spindle holder having its lower end secured in the said hole and provided at its top with a plate for supporting the cheeses, an upwardly tapering spindle for positioning 15 the cheeses having its lower end portion slidably downwardly in the spindle holder, said spindle having passages for dye which communicate with the said chamber, and a fastening device for locking the spindle in 20 the spindle holder at will.

3. A support for cheeses of yarn, comprising 25 a hollow chamber for dye provided with a spindle holder at its top having a plate for supporting the cheeses, an upwardly tapering spindle for positioning the cheeses having its lower end portion slidable downwardly in the spindle holder and provided with passages for dye which communicate with the said chamber, a plate secured to the spindle below the spindle holder to limit its upward 30 movement, means for limiting the downward movement of the spindle when depressed in the spindle holder to free the cheeses, and a fastening device for locking the spindle in the spindle holder. 35

In testimony whereof we have hereunto set our hands.

JOHN BRANDWOOD.

THOMAS BRANDWOOD.

JOSEPH BRANDWOOD.
